(57) **CLAIM**

The ornamental design for an automobile, as shown and described.

DESCRIPTION

FIG. 1 is a top, front, and left-side perspective view of an automobile according to the present invention;

FIG. 2 is a top, rear, and left-side perspective view thereof;

FIG. 3 is a left-side elevation view thereof;

FIG. 4 is a top plan view thereof;

FIG. 5 is a front elevation view thereof; and,

FIG. 6 is a rear elevation view thereof.

The broken lines shown in the drawings illustrate portions of the automobile that form no part of the claimed design.
